CLAIM

The ornamental design for a body fat analyzer, as shown and described.

DESCRIPTION

FIG. 1 is a perspective view of a body fat analyzer showing my new design;

FIG. 2 is a top perspective view thereof;

FIG. 3 is a front perspective view thereof;

FIG. 4 is a side perspective view thereof, viewed from the left of FIG. 3, the side opposite that shown in FIG. 4 being the mirror image thereof;

FIG. 5 is a rear perspective view thereof; and,

FIG. 6 is a bottom perspective view thereof.
